ASH RECEPTACLE AND CIGARETTE BUTT
SNUFFER

Carl A. Shepard, Des Moines, Iowa

Application November 8, 1940, Serial No. 364,828

7 Claims. (Cl. 131—237)

The principal object of my invention is to provide an ash receptacle for receiving and holding tobacco ashes, cigarette butts and like that has integrally associated with it a handy means for extinguishing a lighted cigarette butt.

A further object of this invention is to provide an ash receptacle having a cigarette butt snuffer that is easily manually operated without soiling the fingers during the extinguishing of a cigarette butt.

A still further object of this invention is to provide an ash receptacle having a cigarette butt snuffer that automatically drops the extinguished cigarette butt into the receptacle portion after the same has been extinguished.

A still further object of this invention is to provide a combination ash receptacle and cigarette butt snuffer that is easy to operate, refined in appearance, economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

Fig. 1 is a side view of my device ready for use.

Fig. 2 is a top plan view of my device.

Fig. 3 is a side sectional view of my device in a position for receiving a cigarette butt.

Fig. 4 is a side view of the upper portion of my device extinguishing a lighted end of a cigarette butt as shown by dotted lines.

Fig. 5 is a side view in section of the upper portion of my device taken on line 5—5 of Fig. 3.

There are many types of ash receptacles in general use. Most of these containers are either open at their tops or have a closing trapdoor. In either type no means is provided for immediately extinguishing the lighted end of the cigarette butt at the time it is placed within the receptacle. I have overcome such objections by providing an easily operated mechanism that compresses and extinguishes the cigarette butt at the time it is deposited within the receptacle.

Referring to the drawing, I have used the numeral 10 to designate a cup portion which forms the base portion of my device. This cup portion may be placed to rest upon the table or like supporting surface or it may be secured or mounted to a standard resting on the floor or like. The numeral 11 designates the upper de-

datchable cover portion as shown in Fig. 3. The numeral 13 designates a vertical collar integrally formed on the top of the lid 11 and embracing a hole 14 extending completely through the lid 11 as shown in Fig. 4. The numerals 15 and 16 designate two spaced apart U-members secured to the inside bottom of the lid 11. These U-members extend vertically downwardly and are positioned diametrically opposite from each other 5 at each side of the opening 14. The numeral 17 designates an inverted cup member having an opening 18 in its end wall and slidably mounted in and through the collar 13 and hole 14 as shown in the drawing. The numeral 19 designates a bar member hingedly secured between its two ends on a shaft 20 which is secured to the lower portion of the inverted cup 17 as shown in Fig. 3. The upper end portion of this bar 19 terminates just below the inside bottom of the 10 inverted cup 17 and its lower end portion extends through and slides on the horizontal bottom portion of the loop U-member 15. In general, the length of the member 19 extends downwardly and to the left. The numeral 21 designates a similar bar member hingedly secured between its two ends on the shaft 22 which is secured to the bottom portion of the inverted cup member 17 as shown in Fig. 3. This bar 21 has its upper end terminating just below the 15 inside bottom of the inverted cup member 17 and its lower end portion slidably engaging the bottom center portion of the U-member 16. In general the member 21 extends downwardly and to the right. The pivot points of the two bar members 19 and 21 are diametrically opposite from each other on the lower end portion of the inverted cup member 17 as shown in the drawing, and cut away portions 23 are provided in the lower portion of the inverted cup member to 20 permit the movement of the two members 19 and 21. Under normal conditions the two members 19 and 21 will be spaced apart and in a plane at each side of the opening 18 as shown in Fig. 3. The numeral 24 designates a coil spring having one end connected to the lower portion of the bar 19 and its other end connected to the lower portion of the bar 21 for yieldingly holding the two lower end portions of these two bars toward each other. By virtue 25 of the action of this spring 24, the two bar members 19 and 21 will slide upwardly on the hangers 15 and 16, thereby carrying the inverted cup member 17 to the elevated position shown in Fig. 3. The upward movement of the inverted cup member 17, however, will be limited by the 30

shafts 20 and 22 or the bars 19 and 21 engaging a stop collar 25 on the inside bottom of the inverted cup 17. Obviously if the inverted cup member 17 is manually forced down, it will be against the yielding action of the spring 24 and the lower end portions of the bars 20 and 21 will spread further apart by sliding action on the hangers 15 and 16, thereby bringing the two upper end portions of the bars 19 and 21 together as shown in Fig. 4. By releasing pressure on the inverted cup member 17, the spring 24 will automatically return the inverted cup member to an elevated position and the upper end portions of the bars 19 and 21 in a spread position.

To operate my device, it is merely necessary to stick the lighted end of a cigarette 26 through the hole 18 and in a position between the two upper end portions of the bars 19 and 21 and push downwardly with the same fingers that are holding the cigarette butt on the inverted cup member. This downward movement of the inverted cup member will force the two upper end portions of the bars 19 and 21 together on the ignited end of the cigarette thereby flattening, snuffing or pinching the lighted end of the cigarette and extinguishing it. When the two bar members 19 and 21 are in such positions, their upper end portions will be parallel with each other at each side of the lighted end of the cigarette as shown in Fig. 4. By releasing pressure on the inverted cup 17 and releasing the cigarette butt, the two upper end portions of the bar arms 19 and 21 will separate, thereby permitting the cigarette butt to fall downwardly and into the receptacle portion of the device. The placement of the cigarette butt in the receptacle and the extinguishing of the same is accomplished with one movement of the hand holding the cigarette butt.

Some changes may be made in the construction and arrangement of my improved ash receptacle and cigarette butt snuffer without departing from the real spirit and purpose of my invention, and it is my intention to cover by my claims any modified forms of structure or use of mechanical equivalents which may be reasonably included within their scope.

I claim:

1. In a device of the class described, an inverted cup member having an opening in its end wall and adapted to be slidably mounted in a wall of a container, two spaced apart jaw members hingedly secured to said inverted cup member, and a means for yieldingly holding said two jaw members apart and said inverted cup member in an elevated position of its sliding movement.

2. In a device of the class described, an inverted cup member having an opening in its end wall and adapted to be slidably mounted through a wall of a container, two supporting members within such container, a bar member hingedly secured to the lower portion of said inverted cup member having its lower end slidably engaging one of said supporting members and its other end terminating within said inverted cup member, a second bar member hingedly secured to the lower portion of said inverted cup member having its lower end slidably engaging the other said supporting member, and its upper end portion terminating inside said inverted cup member; said inverted cup member, said bars and said supporting members being so arranged that when said inverted cup member is in a lowered position the upper ends of said bars will be closely adjacent to each other and when said inverted cup mem-

ber is in an elevated position said bar members will have their upper portions spaced relatively far apart, and a means for yieldingly holding said inverted cup member in an elevated position.

3. In a device of the class described, an inverted cup member having an opening in its end wall and adapted to be slidably mounted through a wall of a container, two supporting members within such container, a bar member hingedly secured to the lower portion of said inverted cup member having its lower end slidably engaging one of said supporting members and its other end terminating within said inverted cup member, a second bar member hingedly secured to the lower portion of said inverted cup member having its lower end slidably engaging the other said supporting member, and its upper end portion terminating inside said inverted cup member; said inverted cup member, said bars and said supporting members being so arranged that when said inverted cup member is in a lowered position the upper ends of said bars will be closely adjacent to each other and when said inverted cup member is in an elevated position said bar members will have their upper portions spaced relatively far apart, and a coil spring having one end connected to the lower portion of one of said bar members and its other end connected to the lower portion of said other bar member for yieldingly holding the upper ends of said bar members apart, and said inverted cup member in an elevated position.

4. In a device of the class described, an inverted cup member having an opening in its end wall and adapted to be slidably mounted through a wall of a container, two supporting members within such container, a bar member hingedly secured to the lower portion of said inverted cup member having its lower end slidably engaging one of said supporting members and its other end terminating within said inverted cup member, a second bar member hingedly secured to the lower portion of said inverted cup member having its lower end slidably engaging the other said supporting member, and its upper end portion terminating inside said inverted cup member; said inverted cup member, said bars and said supporting members being so arranged that when said inverted cup member is in a lowered position the upper ends of said bars will be closely adjacent to each other and when said inverted cup member is in an elevated position said bar members will have their upper portions spaced relatively far apart, and a means for yieldingly pulling the lower end portions of said two bar members toward each other.

5. In a device of the class described, an inverted cup member having an opening in its end wall and adapted to be slidably mounted through the top of a container, two hanger members inside such container and positioned diametrically opposite from each other at each side of said inverted cup member, a bar member hingedly secured between its two ends to the lower portion of said inverted cup member having its upper end terminating within the inverted cup member and its lower end supported by and slidably riding on one of said hangers, a second bar member hingedly secured between its two ends to the lower portion of said inverted cup member having its other end terminating within said inverted cup member and its lower end portion supported by and slidably riding on said other hanger member, and a coil spring extending between the lower portions of said two bar members.

6. In a device of the class described an inverted cup having an opening in its end wall and adapted to be slidably mounted in a wall of a container, jaw members disposed at least in part within said inverted cup and pivotally mounted on said inverted cup and yieldable means for maintaining said inverted cup in an outward position of its slide movement.

7. In a device of the class described a shell portion having openings in generally opposite portions of its wall structure adapted to be slidably mounted in a wall of a container and pivotable jaw members disposed within said shell and mounted on said shell.

CARL A. SHEPARD.
